DESIGN FOR A WATCH CLEANING TRAY

Roy R. While, Chicago, Ill., assignor to Henry Paulson and Company, Chicago, Ill., a copartnership

Application June 29, 1946, Serial No. 131,194

Term of patent 3½ years

(Cl. D42—1)

To all whom it may concern:

Be it known that I, Roy R. While, a citizen of the United States and a resident of Chicago, in the county of Cook and State of Illinois, have invented a new, original, and ornamental Design for a Watch Cleaning Tray, of which the following is a specification, reference being had to the accompanying drawing, forming a part thereof, and in which:

Fig. 1 is a perspective view of a watch cleaning tray showing my new design;

Fig. 2 is a side elevational view of the same;

Fig. 3 is a top plan view of the same.

I claim:

The ornamental design for a watch cleaning tray, as shown.

ROY R. WHILE.
